UNITED STATES PATENT OFFICE

2,120,230

RESPIRATOR

Harvey S. Cover, South Bend, Ind.

Application August 10, 1933, Serial No. 684,503

7 Claims. (Cl. 128—146)

My invention relates to improvements in respirators, and has for an object the provision of a device having a flexible body throughout, and the provision of filter chambers laterally disposed relative to the position of the nose of the wearer. It also has for an object the provision of enlarged filter chambers.

The present application is a continuation in part of my co-pending application Serial No. 682,929, now Patent No. 2,000,064, issued May 7, 1935.

Heretofore it has been customary in making devices of this character to include in the body of the same metal stiffening material for the purpose of giving the desired shape to the article. Filter chambers have been attached to respirators before, but they have been attached by metal threaded rings or some equally expensive means. The respirator bodies have been made of rubber, but even when made of rubber a metal ring has been attached to the rubber body for the purpose of attaching the filter chambers. An object of my invention is to dispense with metal in the entire body of my device. By doing this I am able to provide a device which is easily foldable, may be shipped in a smaller container, and may be carried easily in a pocket of the user. Since the body is made of flexible rubber, it will not get out of shape and be rendered unsatisfactory for its intended purposes.

Heretofore most respirators have included an exhaust valve which may be of the type commonly known as a flutter valve, and the provision of these valves has always been an item of large expense. By placing enlarged filter chambers on each side of my device I have found that the user may inhale more freely and may exhale easily without the use of an exhaust valve of any kind whatsoever.

Other objects will appear hereinafter.

My invention may be best understood by reference to the accompanying drawings, in which: Fig. 1 is a perspective view of my device attached to the face of a wearer;

Fig. 2 is a top plan view;

Fig. 3 is a side elevational view;

Fig. 4 is a sectional view, taken substantially on the line 4—4 of Fig. 2;

Fig. 5 is a sectional view, taken substantially on the line 5—5 of Fig. 2;

Fig. 6 is a sectional view, taken substantially on the line 6—6 of Fig. 3; and

Fig. 7 is a view, partly in section and partly in elevation, and taken substantially on the line 7—7 of Fig. 6.

Referring now to the drawings, my device comprises a main body 10 which is preferably molded in an entire unitary body of flexible rubber, and has generally a shape of a wedge, as shown in Fig. 2. The side walls of body 10 include cutouts 11 at the rear top and bottom edges, and because of these the device is reversible, for each of the cutouts provides an opening for the entrance of the nose. Disposed laterally from cutouts 11 are bowed or bell shaped portions 12 which cause the device to fit a great variety of features. When the device is in the position shown in Fig. 1 the cutout 11 fits the nose, and bell shaped portions 12 are adapted to cause a close fit between the cheeks and the nose. At this time the lower 15 cutout 11 and bell shaped portions 12 cause a close fit of the main body 10 on the chin of the wearer, and since the bell shaped portions 12 have inwardly extending flanges 13, a close fit is obtained at all points without the use of an 20 inflated rubber tube which is used in many types of respirators.

As can be clearly seen from Figs. 2 and 6, side walls 14 of body 10 extend diagonally inwardly and finally converge in a thickened lip or bill portion 15. Extending laterally from each side wall 14 is a circular ring or flange 16. Each of these flanges carries on the side thereof laterally extending attaching bosses 17 which may be of a generally elongated shape, as shown clearly in Fig. 2. 30 Bosses 17 may be placed in spaced relation to each other around the periphery of flange 16 so as to provide attaching means for a metal cap 18, preferably made of aluminum. The side walls of cap 18 are preferably provided with elongated 25 slots 19, conforming generally to the shape of bosses 17 for the purpose of encompassing said bosses. Cap 18 is preferably provided with an enlarged centrally disposed aperture 20 in its end wall 21. A metal screen 22 is preferably 40 inserted in cap 18 and abuts against end wall 21 and covers aperture 20. Beneath screen 22, as shown in Fig. 6, may be placed filtering material 23. The side walls 14 of body 10 are preferably provided with apertures 24 immediately beneath 45 filtering material 23 and within the surface enclosed by flange 16, and thus air passages are provided through apertures 24, filtering material 23, screen 22, and aperture 20. In cases where several different kinds of filtering material are 50 required, they may be placed upon apertures 24 and within the compass of flange 16, and may be covered by a cap similar to cap 18 and having a greater vertical dimension. Heretofore filtering chambers have been disposed centrally of the 55

face of the user, and when extensions have been desired they of course protrude forwardly, extend in the line of vision, and place additional stress on the head supporting straps, since they are so far removed from the point of attachment. It can be seen that my filter chambers are closer to the rear edge of body 10, and consequently do not extend into the line of vision.

Adjacent the rear edges of side walls 14, and substantially centrally thereof, may be placed attaching strap supporting bolts 25 and nuts 26, which support strap 27, strap 28, and buckle 29. Straps 27 and 28 are preferably made of elastic material.

15 As has been stated above, the front portions of walls 14 converge and form a thickened bill or lip 15. When it is desired to employ a flutter valve, this lip may be slit along the line of convergence, and would present the appearance shown generally in Fig. 5, but should not be extended rearwardly beyond the line S—S in Fig. 5. To the rear of lip 15, and on the insides of walls 14 reinforcing bosses 30 may be placed. Bosses 30 are seen clearly in Figs. 5 and 6, and extend laterally across the line of meeting of side walls 14; they serve to strengthen the device at this point, and also serve to keep the side walls separated to some extent, even though the rear edges are pulled apart. This feature is quite useful 30 when lip 15 is slit to provide a flutter valve, for if the side walls 14 were close together a disagreeable noise would be made by the flutter valve when the user exhaled through the flutter valve.

It is thought that the use and operation of the device is clear from the foregoing description and drawings, and hence no further explanation will be given.

It has been found that most kinds of filtering material are more efficient when the velocity of the air passing through them is quite low, and since my device provides a large total filtering surface area it can be seen that the efficiency of the device will be considerably enhanced because the velocity of air passing through them will be considerably reduced.

Having thus described my invention, what I claim as new and desire to secure by Letters Patent is:

1. A device of the character described comprising a wedge-shaped body portion formed of flexible material and having substantially flat plane-like side walls converging in a narrow end, a face entrance opening at the wide end of said body portion, nose entrance notches at the top and bottom of said wide end, air entrance openings in the side walls of said body portion, filtering material over said air entrance openings, means for holding said filtering material in place, said wedge-shaped body portion being foldable along a line passing longitudinally thereof intermediately between its side walls and through the narrow end of said wedge-shaped body portion.

2. A device of the character described comprising a substantially wedge-shaped body portion formed of flexible material and having substantially plane-like side walls converging in a narrow end, a face entrance opening at the wide end of said wedge-shaped body portion, air entrance openings in the side walls of said wedge-shaped body portion, filtering material arranged over said last mentioned openings, means for holding said filtering material in place, said

wedge-shaped body portion being foldable along a line passing intermediately between said side walls and through the narrow end of said wedge-shaped body portion.

3. A device of the character described comprising a substantially wedge-shaped body portion formed of flexible material and having substantially plane-like side walls converging in a narrow end, a face entrance opening at the wide end of said wedge-shaped body portion, air entrance openings in the side walls of said wedge-shaped body portion, filtering material arranged over said last mentioned openings, means for holding said filtering material in place, said wedge-shaped body portion being foldable along a line passing intermediately between said side walls and through the narrow end of said wedge-shaped body portion, and a flutter valve formed in the narrow end of said main body portion and of the same material as said main body portion.

4. A device of the character described comprising a main body portion, a face entrance opening and symmetrical side and top and bottom walls, nose receiving portions in said top and bottom walls, said device being adapted for use with its top wall at the top or in the position given with the device rotated through 180°.

5. A device of the character described comprising a main body portion, a face entrance opening and symmetrical side and top and bottom walls, nose receiving portions in said top and bottom walls, said device being adapted for use with its top wall at the top or in the position given with the device rotated through 180°, and a flutter valve formed by forward ends of the side walls and equally operative and effective when the main body section is in either of the positions just described.

6. A device of the character described, comprising a hollow, wedge-shaped body portion having substantially plane-like side walls and an enlarged opening at the wide end thereof, cut-outs at the top and bottom of said open end and adapted to serve as nose entrance notches, openings in the flat plane-like side faces of said body portion, filter material covering said openings, and means for holding said filter material in place, said wedge-shaped body portion being foldable along a line passing longitudinally of and substantially intermediately between said side walls and through the narrow end of said body portion.

7. A device of the character described comprising a hollow, wedge-shaped body portion having an enlarged opening at the wide end thereof, cut-outs at the top and bottom of said open end and adapted to serve as nose entrance notches, openings in the flat, plane-like side faces of said body portion, filter material covering said openings, and means for holding said filter material in place, said last mentioned means comprising laterally extending flanges of resilient and collapsible material bounding the surfaces in which said openings are located, protruding lugs extending outwardly from said flanges, and cap members having enlarged air entrance openings therein and lug engaging slots in the side walls thereof for engagement by the lugs on said flanges, said flanges being sufficiently resilient to hold said lugs in said slots and also being sufficiently collapsible to withdraw said lugs from said slots when collapsed.

HARVEY S. COVER.

DISCLAIMER

2,120,230.—*Harvey S. Cover*, South Bend, Ind. RESPIRATOR. Patent dated June 14, 1938. Disclaimer filed March 20, 1943, by the inventor.
Hereby enters this disclaimer to claims 2 and 3, in said specification.
